UNITED STATES PATENT OFFICE.

HAROLD BARKER, OF ANN ARBOR, MICHIGAN.

DESIGN FOR A BASSINET.

47,415.

Specification for Design.

Patented June 8, 1915.

Application filed February 18, 1915. Serial No. 9,192. Term of patent 14 years.

To all whom it may concern:

Be it known that I, HAROLD BARKER, a citizen of the United States of America, residing at Ann Arbor, in the county of Washtenaw and State of Michigan, have invented a certain new, original, and ornamental Design for a Bassinet, of which the following is a specification, reference being had therein to the accompanying drawings forming part thereof.

The figure is a perspective view of a bassinet, showing my new design.

I claim:

The ornamental design for a bassinet, substantially as shown.

HAROLD BARKER.

Witnesses:

E. B. NORRIS,
ERMINE O'HARA.
